PAINT BRUSH

Claud Thomas, Portland, Oreg., assignor of one-half to Henry C. Olsen, San Francisco, Calif.

Application April 11, 1938, Serial No. 201,339

4 Claims. (Cl. 15—128)

This invention relates to a painting brush and method and has for its objects the provision of an improved brush and method for painting surfaces, which brush upon actuation thereof in a normal manner, causes a predetermined amount of paint to flow to the outer ends of the bristles irrespective of whether the brush is positioned with the bristle ends directed upwardly, laterally or downwardly, and which brush is simple, economical to make and use. Other objects are the provision of improved means for causing a uniform distribution of paint to the painting ends of the bristles and an improved construction that enables a ready replacement or interchange of bristles and other parts, as may be desired. Other objects and advantages will appear in the drawings and description annexed hereto.

In the drawings, Fig. 1 is an elevational view of my improved brush with a tank and connecting pipe semi-diagrammatically illustrated, and with the brush partly in section to illustrate its construction.

Fig. 2 is a sectional view taken along the line 2—2 of Fig. 1, the brush handle being broken in length.

Fig. 3 is a sectional view taken along the line 3—3 of Fig. 1.

Fig. 4 is an elevational view of a modified form 30 of brush, partly in section and with the handle broken in length.

Fig. 5 is a sectional view of Fig. 4 taken along the line 5—5 thereof.

Referring to Figs. 1 to 3, the form of the invention therein illustrated comprises a handle 1, externally in the shape of the handle of an ordinary painter's brush, which handle carries the bristles 2 by a special flexible connection, generally designated 3, disposed between the 40 bristles and handle.

The connection 3 comprises an elongated plate 4 extending along and secured by screws 5 to the cross head 6 of the handle, said plate being formed with a continuous flange 7 adjacent the edges thereof extending outwardly of the plate in direction away from the handle thereby providing an outwardly opening recess 8 enclosed at its sides by the flange and by plate 4 at the closed side. A plate 9 extends over the open 50 side of the recess 8, which plate 9 is formed adjacent its edges with a continuous flange 10 projecting toward and following the contour of flange 7, thus providing an open sided recess 11 similar to recess 8, but opening toward the open 55 side of the latter recess.

A flexible bellows 12 connects between the plates 4, 9, which bellows may be of any suitable flexible material such as leather, rubber, or composition material relatively impervious to the passage of air and paint. The opposite ends of the bellows adjacent the opposite free edges enclose the flanges 7, 10 and are secured against the outer sides of the flanges by metal strips 13, 14, the strips 13 being secured by screws, as indicated, to flange 7, and strips 14 being similarly secured to flange 10, whereby the ends of the bellows are securely clamped against the flanges. Along one of the correspondingly disposed elongated portions of flanges 7, 10 the bellows side is substantially straight and connects said portions fairly close together, but the opposite end sides of the bellows progressively widen toward the side of the bellows opposite the aforesaid straight side. Said end sides and opposite side are formed to double on themselves inwardly toward the central longitudinal axis of the brush upon oscillating plate 9 about an axis extending longitudinally through the straight side of the bellows, which oscillation is permitted by reason of the flexibility of the 25 straight side where it extends across between the flanges and the degree of oscillation of plate 9 is limited by the width of the bellows along the folding side thereof as is apparent from Fig. 2, and which oscillation is to one side only of 30 the longitudinal axis of the brush.

Opposite flange 10, the plate 9 is formed at its ends with end members 15 projecting oppositely of the flange toward the outer end of the brush, and plate 9 is centrally formed with a 35 passageway 16 extending through an externally threaded boss 17 projecting in the same direction as members 15. A cylindrical cap 18 threadedly engages the threads on boss 17, the head of which cap is spaced over and extends across the outer end of the boss and is provided with a central aperture 19 disposed in axial alignment with passageway 6. Around the aperture 19, the head of the cap is extended to form an externally tapered nozzle 20.

The bristles 1 of the brush are secured at their inner ends in an elongated block 21 that is centrally formed with a slot extending longitudinally thereof, which slot is fitted with an insert 22. The insert 22 clamps between its side edges and 50 the sides of the slot in block 21, the flared end 23 of a flattened, flexible conduit 24.

The conduit 24 is generally of rectangular shape, one open end extending parallel with and spaced from the outer end of the body of bristles 55

1, said conduit being fully enclosed within said body of bristles and disposed centrally therein. The side of insert 22 enclosed by the diverging walls of the conduit and said walls, form an 5 elongated chamber 25 (Fig. 2) extending transversely of the brush almost from one side edge thereof to the other. From the point spaced above said insert where the walls of the conduit come substantially together, said conduit walls 10 are secured together along spaced lines 26 (indicated by dotted lines in Fig. 1), extending parallel with the bristles of the brush, thereby forming a row of small ducts 27 leading from chamber 25 to adjacent the outer ends of the central duct of the row may progressively be increased in diameter for a purpose later described.

The brush assembly outwardly of plate 9, which includes the bristles, insert 22 and block 20 21 are removably supported on plate 9 by a strip 28 of sheet metal extending around the block 15 to which it is secured by any desirable means, such as nails 29, and which strip extends outwardly of said block at one side to form a socket 25 adapted to slide over the end members 15 on plate 9 and to enclose the area between the insert 22 and plate 9. Screws 30 removably secure said strip to said members 15 thus rigidly securing the bristle carrying part of the brush to the plate 9.

The insert 22 is centrally formed with a through passageway 31 that is adapted at one end to seat closely against the tapered outer sides of the projecting portion 20 around the passageway 19 that extends through the head of cap 18, and the sides of the end of the passageway 31 opening into chamber 25 is outwardly flared.

Within the passageway 16 through boss 17, and at the end of said passageway adjacent the end opening into recess 11, is a spider 33 centrally formed with a threaded opening for threadedly supporting therein one end of a screw 34, which screw extends outwardly of the opposite open end of said passageway 16 at its opposite end. The said opposite end of the screw 45 supports a circular flexible disk valve 35, the outer margin of which disk normally engages the outer edges of the boss around said passageway 16.

The disk 35 is clamped between nuts threaded on screw 34, and thus is adjustable along said screw so as to vary the tension of the disk against the boss.

Plate 4 is formed with a central opening therefrom which opening a pipe 36 extends through handle 1 out of the end of the handle, said pipe 55 36 being preferably formed integrally with the plate 4 or at least rigidly secured thereto. To the outer end of pipe 36 is secured one end of a flexible hose 37 that connects with a valve 38 on an outlet pipe 39 in the bottom of a paint 60 supply tank 40. The supply tank 40 is portable and is provided with hooks 41 for suspending the tank from a strap 42 that is adapted to be strapped to the body of the operator.

65 At the point of the opening of pipe 36 into the recess 8 a valve 35' is provided, similar in construction to valve 35 and supported in the same manner on a screw 34' supplied on a spider 33', the margin of the opening covered by the valve being slightly recessed to receive the valve.

In the form of invention illustrated in Figs. 4, 5, the principal difference in construction is in the connection between the handle and bristle 75 supporting portion of the brush.

The handle 1' carries a plate 4' and pipe 36' in the same manner as in the previously described device, in which the disk valve 35'' is carried by a spider 33'' positioned in the pipe 36', the valve closing against the end of the central aperture opening into recess 8'.

Flanges 7' on plate 4' support against their free outer edges the margins of a flexible diaphragm 44, said margin being secured thereto by strips 4, 5.

Said diaphragm is centrally apertured to pass the end of an annular shoulder 47 formed around a central passageway 16' in a plate 9' which, plate is disposed similar to the plate 9 of Fig. 1. The margins of diaphragm 44 around said central aperture therethrough are secured around shoulder 47 by a clamping nut 48 threaded onto said shoulder.

On the opposite side of plate 9' from the shoulder 47 is a boss 17', cap 18', and valve 35'' 20 therein, identical in construction with the construction of the corresponding element shown and described in Fig. 1.

Plates 4', and 9' are hingedly secured together along one side by hinges 50 (Fig. 5) so as to 25 permit the plates to oscillate relatively in the same general manner as described for the device shown in Figs. 1 to 3. Except for the diaphragm 44 and hinges, the device of Figs. 4, 5 are substantially the same as in Figs. 1 to 3, and similar 30 parts are similarly numbered, except for bearing prime marks.

In the operation of the device of Figs. 1 to 3, when the container 40 is filled with paint, and the valve 38 is opened, a through passageway for 35 the paint is provided through hose 37 and pipe 36 to communicating recesses 8, 11, the walls of which recesses in combination with the bellows form an expansible chamber between plates 4, 9.

Upon working the brush bristles back and forth 40 over the surface to be painted, the bellows enclosed chamber alternately expands and contracts by reason of oscillation of plate 9. With each expansion, the valve 35' closes and the paint is drawn into said chamber and with each contraction the paint is forced past valve 35 into chamber 25 and from said chamber through ducts 27 for discharge therefrom to the bristles adjacent the outer ends of the latter. Since the ducts 27 are flattened in cross-section in the 50 plane of the brush, they will necessarily tend to assume a circular cross-sectional form as the paint passes therethrough, but their tendency to resume a flattened shape together with the flexing of the conduits with the flexing of the bristles, 55 will act to facilitate the even and uniform extrusion of the paint to the bristles at their outer ends. The plurality of ducts 27 functions to prevent the tendency of the paint to accumulate in a large quantity at one edge of the brush when 60 the brush is held in laterally extending position for lateral movement thereof in painting. Such tendency is, of course, not present when the brush is held vertically for painting a floor or ceiling.

The amount of paint delivered to the bristles 65 is regulated by regulation of valve 38, and valve 35, or by either, but the adjustment of the latter valve is for more accurate regulation than the valve 38.

From the foregoing explanation, it is apparent 70 that the alternate creation of pressure and partial vacuum in the bellows chamber is what causes the delivery of paint to the bristles, and there is no external source of pressure on the paint, such as in the tank 40, or in a compres- 75

sible handle, to cause said delivery. Thus the control of the paint, once the proper adjustment is made, is entirely automatic, and when actuation of the brush stops the delivery stops irrespective of pressure or release by the handle grasping fingers or hand of the operator. Likewise the delivery is independent of any pressure of the handle grasping hand or fingers of the operator.

10 In the device of Figs. 4, 5, the action is the same. The diaphragm 44 is preferably slightly elastic so as to permit the expansion and contraction of the chamber between the same and the side of plate 4', and the flexibility of disk valves 35, 35' (Fig. 1) or valves 35", 35''' (Fig. 4) may be increased or decreased by a reinforcement, such as a thin metal or fiber washer, as is common in valves of this character, although the disk itself may be thickened toward the center to provide such result, if found desirable.

Having described my invention, I claim:

1. A painting brush comprising a handle, a body of bristles on the handle, a passageway extending through said handle and opening at one end into said body of bristles, a portion of said passageway being enlarged with one of the walls of said portion being flexible, hinge means swingingly mounting said body on said handle adjacent said one of the walls arranged and adapted to permit swinging of said body relative to said handle and to cause distortion of said one of the walls upon said swinging to thereby enlarge and restrict the area of said portion whereby pressure will be transmitted to the paint in said portion for forcibly urging said paint outwardly of the passageway.

2. A painting brush comprising a rigid handle, a body of paint distributing bristles, a passageway extending through said handle, a duct in said body opening at one end into the body adjacent the paint distributing ends of the bristles, an enlarged chamber connecting between the opposite end of said duct and passageway for passage of paint from the passageway through said chamber to said duct, means hingedly connecting said body and handle for permitting oscillation of the body relative to the handle upon reciprocation of the body against the surface to be painted, and one of the walls of said chamber

being responsive to oscillation of said body for movement thereof to contract and enlarge the area of said chamber upon opposite movement of the body during reciprocation thereof whereby paint within the chamber will be forced into said duct upon contraction of the area and a check valve positioned to stop movement of the paint into said passageway upon contraction of the area of said chamber.

3. A painting brush comprising a rigid handle, a body of paint distributing bristles, a passageway for paint extending through said handle open at one end adjacent the body, a duct in said body opening at one end into the body adjacent the paint distributing ends of the bristles and open at the opposite end at a point adjacent said open end of the passageway, a bellows device connecting between said body and handle and forming a communicating passage for paint between said opposite open end of the duct and said open end of the said passageway, and hingedly mounting said body on the handle for actuation of the bellows to force paint therein through said duct and out of the same into said body of bristles, and a source of paint supply connected to said passageway for passage of paint therethrough and into said bellows device.

4. A painting brush comprising a rigid handle, a body of paint distributing bristles, a passageway for paint extending through said handle open at one end adjacent the body, a duct in said body opening at one end into the body adjacent the paint distributing ends of the bristles and open at the opposite end at a point adjacent the said open end of the passageway, hinge means connecting said body with said handle for oscillation of the body relative to said handle, a flexible diaphragm connecting between said body and handle adjacent said hinge means, said diaphragm forming one side of a connecting passageway communicating between the adjacent open ends of the duct and said passageway in the handle and said diaphragm being arranged and adapted to be distorted upon oscillation of the handle for contracting and expanding the area of the connecting passageway for forcing paint therein into said duct upon contraction thereof for causing the paint to pass through the duct and into said body.

CLAUD THOMAS. 50
